UNITED STATES PATENT OFFICE.

LESLIE EDWARD WOODSEND, OF DENVER, COLORADO.

INTERNAL-COMBUSTION ENGINE.

1,051,794.

Specification of Letters Patent. Patented Jan. 28, 1913.

Application filed May 10, 1911. Serial No. 626,214.

To all whom it may concern:

Be it known that I, LESLIE E. WOODSEND, a citizen of the United States, and a resident of Denver, in the county of Denver and State of Colorado, have invented a new and Improved Internal-Combustion Engine, of which the following is a full, clear, and exact description.

This invention relates to a new and improved internal combustion engine of a type adapted to use distillate and crude oil in obtaining power; and more particularly relates to a new and improved firing head.

An object of this invention is to provide an internal combustion engine with an improved firing head, which will vaporize and ignite crude oil or distillate, in a simple and efficient manner, without danger of clogging.

In attaining the object named, this invention consists of a firing head containing a vaporizing and igniting plug of a unique shape and this plug is so arranged that it can not become overheated, thereby eliminating the dangers of "back-firing" and of premature explosions. Furthermore, provision is made for feeding the oil to the vaporizer at a point remote from the combustion cylinder so that any excess of oil which might run off from the vaporizer shall not reach the combustion cylinder without first becoming thoroughly vaporized by contacting further, a heated surface.

In order to secure a thorough mixing of the oil vapor and the air in the combustion cylinder, the vapor is caused to rush into the same with a strong angular movement which imparts a rapid, spirally swirling motion to the contents of the cylinder and effects a uniform diffusion of the vapor before each explosion.

These and further objects, together with the construction and combination of parts, will be more fully described hereinafter and particularly set forth in the claims.

Reference is to be had to the accompanying drawings forming a part of this specification, in which similar characters of reference indicate corresponding parts in all the views, and in which—

Figure 1 is a vertical longitudinal section; Fig. 2 is an enlarged vertical section taken through the firing head; and Fig. 3 is an internal face view of the firing head, showing it removed from the cylinder.

Referring more particularly to the separate parts of this invention as embodied in the form shown in the drawings, 1 indicates an engine bed, which may be of any suitable structure, and in this instance is shown as having mounted thereon a cylinder 2. The cylinder 2 is provided with a crank casing 3, which is preferably entirely inclosed so as to be air-tight. Slidably mounted in the cylinder 2, there is provided a piston 4, which may be of any suitable character, and is operatively connected to a crank 5 rotatably mounted in the crank case 3, by means of a pitman 6. An air inlet may be provided for the crank case 3, of any suitable type, such as the check-valve controlled inlet indicated at 7. The air in the crank case 3 may be forced into the cylinder 2 by the action of the piston 4, through passages 8 leading into the cylinder at inlet ports 9 and of which there may be any suitable number. A peculiar thing to be noted about these passages 8 is that they are spiral, so as to give a swirling action to the air as it comes in, aiding in scavenging the burned gases from the cylinder, the section of Fig. 1 being taken along one of these passages and another passage being shown in dotted lines so that their shape will be apparent. The outlet or exhaust for the cylinder may be of any suitable character, and is indicated at 10.

An important part of this invention consists in the firing head 11, which is of a peculiar structure, and is provided with a combustion chamber 12, in which is located an igniting plug 13. The plug 13 is of truncated conical form, as is clearly indicated in the drawings, and is fluted in a spiral manner, so as to form spiral passages 15 extending along the surface of the plug. The purpose of having these passages spiral is to give a swirling action to the vaporized gases, thus thoroughly mixing them with the air in the cylinder when they enter the same. The plug 13 may be also provided with a central passage 16, extending from front to rear thereof and communicating with the interior of the cylinder 2 at one end and with the interior of the firing chamber 12 at the other end. The firing plug 13 may be pointed on the interior end, so that ignition of gas may be accomplished when the piston moves forward slightly, relieving the pressure of gas in the firing head. The chamber 12 is formed by 110

providing a dome 17 in the firing head 11, and this dome is provided with a series of ridges or flutes 118, whereby the structure can be made much thinner and still be quite strong, and whereby the heat-absorbing properties of the dome are materially increased in case it is subjected to exterior heat. The dome 17 is incased by a casing 18, so as to form a chamber therearound, and this casing is provided with openings 19 and 20, whereby a blow-torch or other device can be inserted to heat the dome and ignition chamber in starting the engine before the necessary heat has been generated by the explosions in the engine. The ribs on the outside of the dome will cause the dome to become more quickly heated than would be the case if they were not there. The crude oil or distillate is let into the igniting chamber 12 through an inlet 21, which is supplied by means of a nipple 22. At the bottom of the dome 17, there is provided an outlet, which is normally closed by a clean-out plug 23, which, however, is detachably connected to the dome 17, as by means of a screw-threaded connection, so that it can be readily removed for the purpose of cleaning out the asphaltum or other residue left and deposited by the igniting fuel. A suitable pump or other device may be attached for cleaning out asphaltum or other residue automatically. A similar plug, indicated at 24, may be provided for the cylinder 2, for the same purpose. Suitable oil cups 25 and 26 may be provided for oiling the cylinder 4 and the moving parts in the crank case 3. The primary purpose of causing this air to pass into the combustion cylinder 2, in a state of rapid rotation, is to augment the cooling effect thereof upon the large end of the plug 13 between explosions, so as to prevent the overheating of the plug, but an accompanying advantage is the thorough scavenging of the cylinder 2 of the foul gases after each explosion, and these gases escape through the exhaust 10. A cleanout plug for the exhaust passage is indicated at 24.

A particular point of advantage in this invention lies in the construction of the plug 13 which has a large area exposed alternately to the heating action of the exploding gases, and to the cooling action of the inrushing air. The heat is rapidly conducted to the small end, or tip, of the plug 13, where the radiating surface in proportion to the cross-section is much greater than is the case at the large end, or base of plug 13. Therefore, the actual amount of heat transmitted into the surrounding space 12, and hence available for ignition, is greater at the tip than at the base. Furthermore, a very appreciable difference in actual temperature between the tip and base of the plug 13 results, because of the closely con-

fined space around the tip, and the large open space of the cylinder 2, subject to the periodical inrushes of cold air, to which the base is exposed.

By taking advantage of the facts just explained, it is possible by careful computation to determine such relative proportions between the tip and the base of plug 13 as will give just the right results in vaporizing any certain fuel and in timing the explosions thereof to the proper moment. Obviously, by the means explained, I obtain results much more positive, and under more definite control than has heretofore been possible in the designing of oil engines.

In operating my engine the oil enters from the inlet 21 and strikes the upper surface of the heated plug 13 near the middle point between the base and the tip thereof, where vaporization of the fuel immediately begins and continues as the fuel runs down and around the plug toward the tip. The extended period of contact between the plug 13 and the fuel insures the maximum vaporization. Any excess fuel that may drop from the plug 13 strikes the inner surface of the heated dome 17 where it is further subjected to vaporization or is burned to an ash, which can be removed at intervals through cleanout 23.

In each cycle of the running of my improved engine, the vapor is rapidly generated, by the means already explained, and together with the air which is forced in from the crank case, due to the compressive action of the piston, fills the space 12 under a moderate pressure. When the piston recedes, the reduction in pressure causes the mixture of vapor and air in the space 12 to be ignited at the tip of plug 13 and the rush of fire following the courses of the channels 15, is projected into the combustion cylinder in a series of streams traveling with great velocity and with the swirling motion described above, acting to instantly and completely explode every part of the main charge of vapor and air in the combustion cylinder.

While I have shown one embodiment of my invention, I do not wish to be limited to the specific details thereof, but desire to be protected in various changes, alterations and modifications which may come within the scope of the appended claims.

Having thus described my invention, I claim as new and desire to secure by Letters Patent:—

1. The combination with a cylinder, of a firing head for said cylinder, said firing head having a dome, forming an ignition chamber having a fuel inlet, said dome being fluted on its outer surface, a casing inclosing said dome, forming a chamber therebetween, and a firing plug located in said dome, and having a spirally fluted periph-

- ery forming fuel passages communicating between said ignition chamber and the interior of said cylinder.
2. The combination with a combustion cylinder of a vaporizing and igniting plug suitably incased, the said plug having the form of a tapering body of revolution with two plane bases, the said plug being so located that the larger of the bases, faces the interior of the said combustion cylinder, and that the smaller of the said bases is remote from the said cylinder, means for feeding a fuel to the said plug at a point near the smaller base, and a plurality of spirally disposed channels suitably formed in the lateral surface of the said plug for the purpose specified.
3. In an explosive engine, the combination with a combustion cylinder having an operable piston therein, of an axially aligned

vaporizing and igniting plug of the shape of a right cone, truncated near its vertex to form a blunt tip, and having its base facing into said cylinder, the said plug having spirally disposed channels in the lateral surface thereof and a suitably disposed crank casing having one or more spiral passages therein leading into the said cylinder, the said spiral passages being adapted to guide currents of air into the said cylinder with a swirling motion, thereby to cool the said vaporizing and igniting plug.

In testimony whereof I have signed my name to this specification, in the presence of two subscribing witnesses.

LESLIE EDWARD WOODSEND.
